UNITED STATES PATENT OFFICE.

JACOB B. BLAW, OF PITTSBURG, PENNSYLVANIA, ASSIGNOR TO BLAW COLLAPSIBLE STEEL CENTERING COMPANY, OF PITTSBURG, PENNSYLVANIA, A CORPORATION OF NEW JERSEY.

CENTERING-MOLD.

No. 853,953.

Specification of Letters Patent.

Patented May 21, 1907.

Application filed November 12, 1906. Serial No. 343,006.

To all whom it may concern:

Be it known that I, JACOB B. BLAW, a citizen of the United States, residing at Pittsburgh, in the county of Allegheny and State 5 of Pennsylvania, have invented certain new and useful Improvements in Centering-Molds, of which the following is a specification.

My invention relates to collapsible molds 10 for constructing concrete sewers, conduits, and similar passages; and has for its objects; to provide a mold of flexible material which may be easily collapsed and handled; to provide a mold having superior bracing and 15 collapsing means; and to provide a mold of the above type having improved means whereby it may be moved from one portion of the sewer to another. These and other 20 objects are accomplished by my invention one embodiment of which is illustrated in the accompanying drawings in which,

Figure 1 is an end view of the mold,

Figure 2 is an end view of a modified form 25 of mold, and

Figure 3 is an end view of still another modification.

My device is preferably constructed of thin sheet metal which can be easily handled and which can be detached from the concrete after it has set by a gradual or peeling 30 action. The mold is primarily intended for large size conduits or sewers, in which each member is composed of a plurality of sections for ease in handling, and a thorough 35 system of bracing is necessitated because of the size and flexibility of the plates, but it is obvious that certain of the general features of construction are applicable to molds for forming any size of passage.

Referring first to the form of device as 40 shown in Figure 1, it will be seen that the mold is composed of four sections or plates numbered 1, 2, 3, and 4, which plates are of thin sheet metal secured together and constitute a half of a tube. The sections 2 and 45 3 are connected detachably to the members 1 and 4 respectively by means of the angle 50 irons 5 which angle irons are riveted to the members 2 and 3 and are provided with slots 55 through which the loop members 6 secured to the members 1 and 4, pass and are held 60 in place by means of small wedges (not shown). The two members 2 and 3 are de-

tachably secured together by means of the angle irons 7 which members are secured to 55 the plates 2 and 3 and secured to each other detachably by means of cross bolts. The sections are braced by means of the turn buckles 7', 8, 9, 10, 11, and 12, which turn buckles are necessary for bracing because of 60 the flexibility of the thin metal and are also of use in collapsing the mold after the concrete has set about it. The upper ends of the turn buckles 8 and 12 fit removably into the 65 projecting flanges of the angles 5, which angles similarly received a slight distance further along the ends of the turn buckle 10. The upper ends of the turn buckles 9 and 11 are carried by the angles 13 riveted to the 70 members 2 and 3. Adjacent the lower edges of the plates 1 and 4 are secured the angles 14 which angles are provided with holes for receiving the ends of the turn buckles 7', 8, 9, 11, and 12, it being understood that the various 75 holes for the turn buckles are spaced along the angles 14 so that there will be no interference. Other angle sections 15 and 16 are riveted to the plates 1 and 4 and constitute a means for supporting the wheels 16, such wheels being mounted upon brackets 17 80 secured to the angles 15 and 16 and additionally secured by means of upwardly extending struts 18 also secured at their upper ends to the angles 15. The lower edges of the members 1 and 4 are provided with the inwardly 85 projecting angle irons 19 for resting upon the timbers 20 when the mold is in operative position. The timbers 20 extend along the floor of the sewer which is indicated by the line 21, which floor is laid at the desired level 90 preliminary to the formation of the rest of the mold. The timbers 20 are securely held in position by a transversely extending frame work consisting of the braces 22 also shown in dotted lines. At the sides of the timbers 95 20 other smaller timbers 23 are secured, which members 23 constitute a track on which the wheels 16 run when the mold is collapsed and the walls sprung in so that such wheels 16 are permitted to drop down. The 100 mold is collapsed by tightening the various turn buckles and thereby releasing the grip of the plates upon the concrete to such an extent that the mold will drop down into position for movement along the track member 105 23. The mold can then be moved along its

track into position for forming another length of sewer. It will be understood that the length of the plates constituting the sections of the sewer is made to suit the requirements of handling and that the number of turn buckles arranged side by side in a longitudinal direction will depend upon the length of such section. It will be apparent that the system of bracing shown secures a rigid structure and gives a maximum strength for the material used as each brace extends in substantially a radial direction and tends to resist the deforming strain in the most effective manner. It will also be apparent that the arrangement of braces secures an effectual collapsing when they are contracted in length. Furthermore by securing the braces 8 and 12 to the angles 5, a stiffening of the mold member at the joint is secured, which stiffening is of course, desirable at this place which would otherwise be easily deformed. The wheels 16 provide for the easy transfer of the mold without taking the sections apart and are secured to the mold in such a way that no unnecessary strain is thrown upon the thin members 1, and 2.

In Figure 2 a modified structure is shown which structure differs in that the number of radial braces 24 corresponding to the braces 8, 9, 11, 12, of Figure 1 is increased and the upper ends of such braces are secured in every case to angle joints corresponding to the joint 7, 7 at the top of the mold in Figure 1. The construction also differs from that of Figure 1 in that there are no braces extending horizontally across the mold and corresponding to the braces 7' and 10. These differences are due to the difference in shape of the sewer to be produced and each is obviously better adapted to its form of section than the other would be. The dotted lines in Figure 1 indicate the bottom of the sewer and the wooden frame work similar to that in Figure 1.

In Figure 3 another modification of the structure of Figure 1 is indicated this form of mold being designed for smaller sizes than is Figure 1 and the changes involved are those naturally incident to the reduction in size. Only two members 26 are used to form the mold and the number of braces is reduced to four as indicated in the drawing. Further-

more the brackets carrying the wheels 27 are attached directly to the side members 26 and the stiffening angles 15 of Figure 1 are done away with. In operation the device is substantially the same as that of Figure 1.

Having thus described my invention and illustrated its use, what I claim is new and desire to secure by Letters Patent, is the following:

1. In combination, a parti-tubular mold member of flexible material and radially directed stiffening and collapsing braces extending from the edges of the member to the opposite sides of the mold.

2. In combination, a parti-tubular mold member of flexible material, and a plurality of radially directed stiffening and collapsing braces extending from each of the edges of the member to different points on the opposite walls of the mold.

3. In combination, a parti-tubular mold member of flexible material provided with stiffening sections along its lower edges and radially directed stiffening and collapsing braces extending from the edges of the member to the opposite sides of the mold.

4. In combination, a parti-tubular mold member of flexible material comprising a plurality of sections removably secured together at the edges by flanged stiffening sections and radially directed stiffening and collapsing braces extending from the edges of the member to the flanges of the stiffening sections.

5. In combination, a parti-tubular mold member of flexible material, transversely extending stiffening and collapsing braces secured to the edges of the member, and wheels mounted adjacent such edges.

6. In combination, a parti-tubular mold member of flexible material, stiffening sections extending up from the edges of the member, transversely extending stiffening and collapsing braces secured adjacent the edges of the member, and wheels secured to the stiffening sections.

In testimony whereof, I hereunto sign my name in the presence of the two subscribed witnesses.

JACOB B. BLAW.
